SWAN M. AKEYSON, OF LONG BEACH, CALIFORNIA

JARRING TOOL

Application filed March 27, 1929. Serial No. 350,277.

This invention relates to a jarring tool particularly useful in the drilling of wells and for the removal of bits, or other tools, which become fastened in the hole during the drilling of the well.

An object of my invention is to provide a jarring tool which can be readily coupled to the tool secured in the hole and which will strike against the tool to assist in its removal.

Still another object is to provide a jarring tool which is operable upon moving the drill pipe longitudinally, thus relieving the torque strain on the pipe which is present in the jarring tools heretofore in use.

Other objects, advantages, and features of invention may appear from the accompanying drawings, the subjoined detailed description, and the appended claims.

20 In the drawings:

Figure 1 is a longitudinal sectional view of my jarring tool.

Figure 2 is a longitudinal sectional view of the jarring tool in position to strike the blow against the tool.

Figure 3 is a fragmentary longitudinal sectional view of a slightly modified form of tool.

Referring more particularly to the drawings, the numeral 1 indicates the cylindrical body or barrel of the tool to the upper end of which a tool joint 2 is secured. A post 3 extends into the body 1 through the lower end thereof and this post is adapted to be secured to the bit or other tool. A head 4 is formed on the upper end of the post and this head accurately fits the inner wall of the body 1.

20 A packing ring 5 is provided in the body and presses against the post 3 and a plurality of ducts 6 extend from the interior of the body 1 to the rear of the ring 5. Thus any fluid pressure in the body will tend to press the packing ring tightly around the post 3 and will prevent leakage of the fluid from the outside past the post, and thence into the body.

A bumper bar 7 screws into the top of the head 4 and this bar is provided with an enlarged ring 8, the purpose of which will be

further described. A plurality of spring fingers 9 are mounted upon a sleeve 10 which sleeve is slidably mounted in the body 1. The spring fingers 9 are each provided with an enlarged lug 11, said lugs acting as a stop for the ring 8, as will be further described. A rubber compression ring 12 sets upon a metal collar 13, said collar being limited in its downward movement by a suitable shoulder 14 formed on the inside of the barrel 1.

The joint 2 is provided with a square recess 15 in the bottom thereof and the bar 7 is provided with a squared upper end 16 which fits into the recess 15 and when these members are thus coupled, as shown in Figure 1, the post 3 can be screwed into or out of the lost tool.

The operation of my tool is as follows: The tool is lowered into the well in the position shown in Figure 1, and the post 3 is screwed into the lost tool but the screwed connection need not be very tight. The drill pipe is secured to the joint 2 and is now pulled upwardly, causing the fingers 9 to be pulled downwardly to the position shown in Figure 2. An upward strain is now placed upon the drill pipe and this causes the rubber ring 12 to compress. The lugs 11 then move below the metal collar 13 which permits them to expand outwardly and the bumper bar 7 is suddenly released which permits the body 1 to move rapidly upwardly and strike against the head 4, thus imparting a jar to the tool.

The drill pipe is now lowered and the ring 8 engages the bottom of the lugs 11, thus pushing the fingers 9 upwardly to the position shown in Figure 1 and since there is no restriction to the outward expansion of the fingers the ring 8 will readily pass the lugs 11 and the movement previously recited is repeated.

90 In the modified form shown in Figure 3 the cylindrical barrel 17 is provided with the post 18, identical in construction to the post 3. The head 19 is formed on the post and the bumper bar 20 rises from the head 19. A tool joint 21 is secured to the upper end of the barrel 17. A metal collar 22 is slidably mounted in the barrel 17 and a plurality of spring fingers 23 are adapted to bear upon the ring 22 and these fingers are backed by a

rubber ring 24. Lugs 25 are formed on each of the spring fingers 23 for the purpose of engaging the enlarged ring 26 on the top of the bumper bar 20. The action of the bumper bar in passing the lugs 25 is identical to that previously described.

On the upward movement of the bar 20 the enlarged ring 26 engages the lugs 25, thus pushing the spring fingers and the rubber 10 backing ring upwardly into the slightly enlarged space 27. This permits the fingers to expand readily and the enlarged ring 26 is allowed to pass with little effort.

Having described my invention, I claim:

15 1. A jarring tool comprising a barrel, a post extending into the barrel and slidable therein, packing means in the barrel around the post, a head on the post within the barrel, a bumper bar rising from the head, an enlarged ring on the bumper bar, a plurality of spring fingers, a sleeve to which said fingers are secured, lugs on the fingers adapted to engage said ring, a rubber ring in the barrel, and a metal collar upon which the rubber ring 20 rests, said lugs on the spring fingers being adapted to be positioned opposite the metal collar before the rubber ring is compressed, whereby the lugs are permitted to move below the metal collar and release the enlarged ring 25 on the bumper bar.

2. A jarring tool comprising a barrel, a post extending into the barrel, and slidable therein, packing means in the barrel around the post, a head on the post within the barrel, 25 bumper bar rising from the head, an enlarged ring on the bumper bar, a plurality of spring fingers, a sleeve to which said fingers are secured, lugs on the fingers adapted to engage said ring, a rubber ring in the barrel, and a metal collar upon which the rubber ring rests, 30 said lugs on the spring fingers being adapted to be positioned opposite the metal collar before the rubber ring is compressed, whereby the lugs are permitted to move below the metal collar and release the enlarged ring on 35 the bumper bar, and means adjustably mounting the bumper bar in said head.

3. A jarring tool comprising a barrel, a post extending into the barrel and slidable 40 therein, a head on the post within the barrel, a bumper bar rising from the head, an enlarged ring on the bumper bar, a plurality of spring fingers, means securing said spring fingers together, lugs on the fingers adapted to 45 engage said ring, a rubber compression ring in the barrel, means securing said rubber ring in the barrel, means restraining the outward movement of said spring fingers before the rubber ring is compressed, said fingers being 50 adapted to spread outwardly to release the ring on the bumper bar when the rubber ring is compressed.

In testimony whereof, I affix my signature.
SWAN M. AKEYSON.
